US0D1049866S

(12) United States Design Patent (10) Patent No.: US D1,049,866 S
(45) Date of Patent: * Nov. 5, 2024

(54) DISPENSER

(71) Applicant: Method Products, PBC, San Francisco, CA (US)

(72) Inventor: Louis Filosa, San Francisco, CA (US)

(73) Assignee: Method Products, PBC, San Francisco, CA (US)

() Term: 15 Years

(21) Appl. No.: 29/831,157

(22) Filed: Mar. 17, 2022

(51) LOC (14) Cl. 09-01

(52) U.S. Cl.

USPC D9/694

(58) Field of Classification Search

USPC D9/500, 503, 504, 505, 516, 519, 529, D9/544, 549, 572, 575, 682, 684, 686, D9/688, 690, 691, 692, 693, 694;

(57) CLAIM

The ornamental design for a dispenser as shown and described.

DESCRIPTION

FIG. 1 is a top perspective view of a dispenser showing the claimed design;

FIG. 2 is a bottom perspective view thereof;

FIG. 3 is a right side view thereof;

FIG. 4 is a left side view thereof;

FIG. 5 is a front view thereof;

FIG. 6 is a rear view thereof;

FIG. 7 is a top view thereof; and,

FIG. 8 is a bottom view thereof.

The broken lines in the figures show portions of the dispenser that form no part of the claimed design.

1 Claim, 7 Drawing Sheets
